To all whom it may concern:

Be it known that I, JOSEPH T. BAILEY, a citizen of the United States, residing in the city and county of Philadelphia, State of Pennsylvania, have invented and produced a new and original Design for a Badge, of which the following is a specification, reference being had to the accompanying drawings, forming part thereof.

- The leading feature of my design for a badge is the representation of a bastion inclosing the representation of a field of rays.

In the drawings, A designates a badge, on the face of which is the representation of a bastion B, within which is the representation of a field of rays C.
